UNITED STATES PATENT OFFICE.

JAMES A. CAMERON, OF CHICAGO, ILLINOIS, ASSIGNOR TO EASTMAN KODAK COMPANY, OF ROCHESTER, NEW YORK, A CORPORATION OF NEW YORK.

PHOTOGRAPHIC MOUNT.

Application filed March 3, 1925. Serial No. 12,930.

This invention relates to mounts for photographs and more particularly to easel mounts of the type shown in my Patent, No. 1,396,724, granted November 15, 1921, and my copending application 757,051, filed December 19, 1924. In easels of this type in which the side edges are bent back to form the supporting elements, it is unpracticable to fold these side members over the front area so as to protect a picture therein during shipping or storage. Moreover, when the corner pockets are struck up from the material of the mount and the mounts are packed solidly, there is a tendency for the corner pockets to be crushed down flat into the mount so that it is difficult to slip a corner of a card under them.

Among the objects of the present invention is the provision of flaps or doors that may be folded over a picture to protect the same or which may be folded back to reveal the picture in an artistic manner. Another object is to provide means for holding the pockets out from the mount so that they will not be crushed during storage.

These and other objects are obtained by the provision of an additional member having corners which may be thrust under the pockets holding them out from the mount, and the provision upon the edges of such a member of flaps which may be folded over the display area or may be folded back to reveal the same.

In the accompanying drawing in which the same reference characters denote the same parts throughout;

Fig. 1 is a front view of an easel embodying my invention with the flaps opened.

Fig. 2 is a side view thereof.

Fig. 3 is a view of the flap bearing member in unfolded position.

Fig. 4 is a fragmentary view showing the engagement of the flap bearing member with a corner pocket.

Fig. 5 is a section on the line 5—5 of Fig. 1 and showing the parts in folded condition.

The easel consists of a central body portion 1 having at its side edges flaps 2 which may be bent back into supporting position or may be folded over the rear as shown in Fig. 5. The front portion 1 carries a tongue 3 having locking projections 4 adapted to be bent rearwardly and to engage over the edges of the flaps 2 in the manner described in the above mentioned patent and applica-

tion. The central portion 1 carries corner pockets 5 preferably struck from the material and the area defined by such pockets constitutes a display portion wherein a photograph may be held.

In accordance with my present invention, however, I use a second sheet having a central rectangular portion 6 with corners 7 adapted to engage within the pockets 5. Along two side edges of the portion are flaps 8 which may be folded over said central portions as shown in Figure 5 to protect the same, or may be opened to reveal the display area of the central portion as shown in Figure 1. A photograph 10 separate from the portion 6 may be inserted within the corners above this portion.

It is obvious that the presence of the corners 7 within the pockets prevents their being crushed down into the plane of the support 1. Furthermore, the flaps furnish an attractive setting for the picture and obviously protect it in a desirable manner during storage. These flaps are cut away as indicated at 9 so as to fit in the same plane with the tops of the pockets 5.

The above is by way of example and I contemplate as within the scope of my invention all such modifications and equivalents as fall within the appended claims.

Having thus described my invention, what I claim as new and desire to secure by Letters Patent is:

1. A mount for photographs comprising a supporting sheet having thereon embossed corner pocket members, the space within said members being an exhibiting area, and a second sheet separable from the first and comprising a central portion adapted to be engaged in said corner pockets and having an exhibiting area lying over said first exhibiting area, and having a flap adapted to be folded over said exhibiting areas or to be folded back to render the central portion visible, the flap being shaped so that, when folded down above said area, it will lie in the plane of the pockets and not interfere with the pockets.

2. A mount for photographs comprising a supporting sheet having embossed pockets struck from the material thereof and surrounding an exhibiting area, and a second sheet having corners adapted to fit within said pockets and on said area and hold them out from the first sheet whereby a third sheet

may be readily mounted under said pockets and having a flap adapted to be folded over that portion of the second sheet above said area or to be folded back to reveal said portion, said flap being shaped so that, when folded above said area, it will not interfere with the pockets.

3. An easel mount for photographs comprising a front exhibiting portion and flaps on the sides of said portion adapted to be bent back into position to support said front portion, said front portion having pocket members adapted to embrace the corners of a card, and a sheet having corners to be engaged by said pocket members and having side flaps adapted to be folded over the portion of the sheet within the corners and to be folded back to reveal the same portion, said side flaps being cut away adjacent their inner corners by an amount as great as the area of the corresponding pocket so as to permit said flaps to be folded down into the plane of the pockets without interference therewith.

4. A mount for photographs comprising a supporting sheet having thereon four pocket members adapted to embrace the corners of a card, and a second sheet separable from the first sheet and comprising a central portion having corners adapted to be embraced by said pocket members and having flaps adapted to be folded over said central portion or to be folded back to render visible

the central portion, the pocket members extending forwardly beyond the corners of the second sheet sufficiently to permit the ready insertion of the corners of a picture card beneath said pocket members and above said second sheet, said flaps being cut away opposite each of said pockets by an amount as great as the area of the corresponding pocket, whereby said flaps may be folded down into the plane of the pockets without interference therewith.

5. A mount for photographs comprising a supporting sheet having thereon pocket members adapted to embrace the corners of a card, and a second sheet comprising a central portion having corners adapted to be embraced by said pocket members and having flaps adapted to be folded over said central portion or to be folded back to render visible the central portion, the pocket members extending beyond the corners of the second sheet sufficiently to permit the insertion of the corners of a picture card beneath said pocket members and above said second sheet, said flaps being cut away adjacent their inner corners by amounts as great as the areas of the corresponding pockets so as to permit said flaps to be folded down into the plane of the pocket members without interference therewith.

Signed at Chicago, Illinois, this 26th day of February, 1925.

JAMES A. CAMERON.
